SAMUEL TIMINGS, OF BIRMINGHAM, ENGLAND.

MEANS FOR REMOVING SCRAP FROM SHEET-METAL STAMPINGS.

1,122,666.

Specification of Letters Patent. Patented Dec. 29, 1914.

Application filed January 27, 1914. Serial No. 814,629.

To all whom it may concern:

Be it known that I, SAMUEL TIMINGS, a subject of His Majesty the King of Great Britain and Ireland, residing at 55 Great 5 Hampton street, in the city of Birmingham, England, have invented new and useful Improvements in Means for Removing Scrap from Sheet-Metal Stampings, of which the following is a specification.

This invention has reference to improved means for removing scrap from hollow sheet metal stampings which scrap is surplus metal and which as is well known forms a flange around the margin of the 15 stamping and has to be clipped off or otherwise removed. Heretofore for this purpose it has been customary to employ a pair of top and bottom clipping tools, the bottom tool having a gap or opening correspond- 20 ing in shape and size with the finished stamping without the scrap and having a cutting edge all around the top, while the top tool is made in the form of a punch also with a cutting edge and of the proper shape 25 and size to fit into the bottom tool so that the flanged stamping having been placed on the bottom tool the flange or scrap metal is cut or clipped off all around the stamping by the action of the top tool forcing the 30 stamping into the recess in the bottom tool. Each pair of top and bottom clipping tools can only be used for clipping stampings of the same shape and size, and it therefore follows that sheet metal stampers and pierc- 35 ers have to keep in stock a very large number of various pairs of clipping tools.

Now my invention is directed to provide means for removing the scrap flange or surplus metal from hollow sheet metal stampings without employing any clipping tools 40 so that the cost of making such clipping tools is thereby saved. The appliance which I use for removing the said scrap is applicable for use with all kinds and shapes of 45 sheet metal stampings no matter what is their shape and size.

According to this invention I employ a circular saw suitably mounted to revolve in a plane parallel with a surface plate or 50 table, the distance between it and such surface plate or table being slightly greater than the thickness of the flange scrap metal to be removed. Mounted on or adjacent to the saw spindle and close up against the 55 face of the saw which is farther from the

surface plate or table there is a gage collar or its equivalent so arranged that the periphery of the saw projects beyond the gage collar or its equivalent. The flange of scrap metal is removed from the hollow sheet metal stamping by the stamping being laid face downward on the surface plate or table and pressed up against the periphery of the revolving saw so that the flange will then pass between the face of the saw and the table and the periphery of the saw will saw into the edge or rim of the sheet metal stamping close to the flange and as the stamping is moved along and turned around the whole of the flange will ultimately be removed leaving the sawed edge of the stamping substantially flat and level. The said gage collar or its equivalent gages the distance which the saw projects through the inner side of the rim of the stamping.

The gage collar against which the edge of the stamping is pressed while the saw is removing the scrap is preferably mounted loosely on the clamping collar of the saw so as not to revolve with the saw but to be merely revolved by the friction of the pressure of the stamping against the periphery of the gage collar.

My invention is illustrated by the accompanying drawings of which—

Figure 1 is a plan of a hollow sheet metal ink-stand stamping showing the flange of scrap metal around it which is to be removed; Fig. 2 is a sectional elevation of the same; Fig. 3 is a cross sectional elevation of the same; Fig. 4 is a sectional elevation of the same, with the flange of scrap metal, having been removed therefrom by the saw; Fig. 5 is a plan of the same ink-stand stamping with the flange of scrap metal removed and this latter is shown separately in Fig. 6; Fig. 7 is a sectional front elevation of an appliance constructed in accordance with this invention for sawing off the inner or outer flanges of scrap metal as aforesaid. Fig. 8 is a sectional side elevation of the same; Fig. 9 is a plan of the same; Fig. 10 is a sectional elevation of parts of the same on an enlarged scale so as to show the action of the saw, and the method of mounting the same; Fig. 11 is a sectional side elevation of a slightly modified arrangement of my invention adapted for those stampings in which some part of the stamping projects below the scrap

flange; Fig. 12 is a sectional elevation of portions of a further slightly modified arrangement of the said appliance; and Fig. 13 is a plan of the same.

5 1 is the circular saw which is mounted on the spindle 2 preferably arranged with its axis vertical and which projects through the top surface 3 of a horizontal table or surface plate 4, said spindle 2 being suitably mounted in bearings 5, 6 of the under frame 7 and furnished with a pulley 8 by which the saw spindle can be driven with a half cross belt or the like from a pulley on a lay shaft.

10 15 The plane of the saw 1 is parallel with the plane surface 3 of the table 4 and the distance between the underside of the saw 1 and the face 3 of the surface plate or table is slightly greater than the thickness of the 20 flange 9 of scrap metal which is to be removed, as for instance, from the ink-stand stamping 10 illustrated in Figs. 1, 2, 3, 4, and 5.

25 11 is the gage collar which is made of somewhat smaller diameter than the saw 1 and is preferably adapted to revolve independently of the same. This can conveniently be done by the gage collar 11 being mounted to revolve loosely on the sleeve 12 (Fig. 10) which is made with a flange 13 adapted to fit against the upper face of the saw 1 and press the saw firmly against the face of the collar 14 of the saw spindle 2. This sleeve 12 is secured in place by the 30 nut 15 which is screwed on to the reduced part 16 of the saw spindle 2 and fits easily inside the sleeve 12, said nut 15 being made with a flange 17 to bear against the top end of the sleeve 12 and clamp the same firmly 35 against the saw when the nut 15 is screwed up. The distance between the underside of the collar 17 of the nut and the top surface of the flange 13 of the sleeve 12 is slightly greater than the thickness through the eye 40 of the gage collar 11 so that the latter can thus revolve easily on the sleeve.

45 The periphery of the flange 13 of the sleeve is preferably beveled off toward the bottom as shown and the under face of the 50 gage collar 11 is similarly recessed and beveled off to suit so that the periphery of the gage collar extends down to, or nearly down to, the face of the saw 1 and thus affords a proper bearing for the periphery of any 55 stamping to be pressed against it while the flange 9 of scrap metal is being removed by the saw as aforesaid, the gage collar being held stationary or moved around slowly by the pressure of the edge of the stamping 60 such as 10 against it.

65 The face plate or table 4 is so carried that the distance between its upper surface and the underside of the saw 1 can be adjusted as may be required to suit stampings of various thicknesses of metal. This adjust-

ment can readily be effected by the table top 4 having four screws 18 fixed to or projecting from its underside and passing through holes in lugs 19 formed on the under frame 7, said screws 18 having adjusting nuts 20 and lock nuts 21 so that by adjusting these nuts 20 the distance between the upper side of the table and the underside of the saw can be adjusted to a nicety and when so adjusted the table can be locked 75 in this position by screwing up the lock nuts 21.

In using the appliance above described, the flange 9 of the stamping, such as the ink-stand stamping 10, is preferably first 80 reduced in size as much as possible by being clipped with shears; the stamping 10 is then laid flange downward on the surface plate or table 4 as in Figs. 9 and 10 and by the operator the stamping is slid along the top 85 surface 3 of the surface plate or table 4 so that the flange 9 of the stamping passes between the underside of the saw 1 and the top of the table 4 and the periphery of the saw 1 saws into the rim of the stamping immediately above the flange 9 (as in Figs. 9 and 10) and thus severs the portion of the flange 9 from the stamping 10 as the latter is pressed up against the gage collar 11 and meanwhile turned around so that the saw 90 1 can act all around the stamping. The flange 9 will then have been removed in a piece as in Figs. 4 and 6 leaving the stamping with a perfectly level bottom edge 22 where the flange 9 has been sawed off. 100 When, as is usual, the rim 23 of the stamping is inclined, then the periphery of the gage collar 11 is preferably made inclined as in Figs. 7, 8, 9, 10, and 11 to correspond with the inclination of the stampings. 105

When the stamping (such as 24 in Fig. 11) is of such a shape that one part 25 projects below the bottom or underside of the scrap flange 9, then when the machine is for use with these stampings that portion 110 26 of the table on which the stamping will rest is made separate from the portion 27 of the table immediately under and around the saw and this part 26 can be independently adjusted vertically and set at the 115 proper height for this bulged or lower portion 25 of the stamping to rest upon while the flange 9 of scrap metal rests under the saw upon the top portion 27 of the table which is immediately underneath the saw as 120 shown for instance in Fig. 11. The portion 26 of the table is made adjustable in height as by screws 18 and adjusting nuts 20 and lock nuts 21 similarly as above described with reference to the table top or surface 125 plate 4.

The gage for the edge of the stamping to bear against as the flange of scrap metal is removed by the saw is preferably made in the form of a gage collar mounted on the 130

saw spindle 2 as above described, but it will be evident that any other equivalent arrangement may be adopted for this purpose such for instance as illustrated in Figs. 12 5 and 13, where the gage marked 28 is stationary and is mounted adjacent to the spindle and is made in the form of a bridge bar fixed to the top of the table at 29 with the saw 1 revolving immediately underneath it 10 and close up to the underside of the gage 28.

My invention is illustrated as applied to the removal of an external flange from a sheet metal stamping, but it is to be understood that my invention can be similarly 15 used for removing an internal flange from a trough section sheet metal stamping, for example an oval picture frame, the stamping having a suitable space within the frame through which the gage collar and circular 20 saw can be inserted.

What I claim as my invention and desire to secure by Letters Patent is:—

1. Apparatus for removing a scrap metal flange from a hollow sheet metal stamping, 25 comprising in combination a revolving circular saw, a surface plate fixed a short distance from one face of said saw, and a gage against which the stamping abuts, the cutting edge of the saw projecting beyond the 30 said gage.

2. Apparatus for removing a scrap metal flange from a hollow sheet metal stamping, 35 comprising in combination a revolving circular saw, a surface plate fixed a short distance from one face of said saw, a circular gage collar on the other face of said saw against which the stamping abuts during the sawing process, the edge of the saw projecting beyond the periphery of said gage collar.

40 3. Apparatus for removing a scrap metal flange from a hollow sheet metal stamping, comprising in combination a circular saw fixedly mounted upon a revolving spindle, said saw being set a short distance above 45 a surface plate or table so as to leave a clearance between said saw and plate or table in which clearance the flange to be removed can enter to permit of the teeth of the saw

cutting through the sides of the hollow metal stamping. 50

4. Apparatus for removing a scrap metal flange from a hollow sheet metal stamping, comprising in combination a circular saw mounted upon a spindle, said spindle having rotary motion imparted thereto, a surface plate or table fixed below said saw and having a clearance between the lower face of the saw and the surface of the plate or table, a circular gage collar loosely mounted on said spindle and adapted to frictionally 60 revolve with the saw, said gage collar being stationary when in contact with the sides of the hollow sheet metal stamping from which the flange is to be removed.

5. Apparatus for removing a scrap metal flange from a hollow sheet metal stamping, 65 comprising in combination a circular saw mounted upon a spindle, a pulley fixed to said spindle, an adjustable surface plate fixed below said saw and having clearance 70 between the saw and plate, a circular gage collar loosely mounted on said spindle adapted to frictionally revolve with the saw, said collar being held against revolution when in contact with the sides of the hollow sheet 75 metal stamping from which the flange is to be removed.

6. Apparatus for removing a scrap metal flange from a hollow sheet metal stamping, 80 comprising in combination a revolving circular saw mounted on a spindle, a pulley on said spindle, a surface plate adjustably positioned in relation to said saw, screws on said plate, milled and lock nuts on said screws, a gage collar mounted on said spindle on the opposite face of the saw to the adjustable plate, and a frame or bracket for supporting said spindle and surface plate. 85

In testimony whereof I have signed my name to this specification in the presence of 90 two subscribing witnesses.

SAMUEL TIMINGS.
